VIDEO TAPE CONTAINER

Georg Heeren, St. Paul, Minn., assignor to Blackbourn
Binding Incorporated, St. Paul, Minn.

Filed Feb. 22, 1972, Ser. No. 228,427

Term of patent 14 years

Int. Cl. D3—99

U.S. Cl. D87—1 D

FIG. 1

FIG. 2

FIG. 3

FIG. 4

5 → FIG. 5

FIG. 6

FIG. 7

FIG. 8

FIG. 1 is a perspective view of a video tape container embodying my new design;

FIG. 2 is an end view thereof;

FIG. 3 is a top view thereof;

FIG. 4 is a view showing the container in open position;

FIG. 5 is a transverse section taken substantially along line 5—5 of FIG. 4;

FIG. 6 is a view of the side opposite to that illustrated in FIG. 1;

FIG. 7 is a view of the end opposite to that illustrated in FIG. 1; and

FIG. 8 is an edge view thereof in open position.

I claim:

The ornamental design for a video tape container, substantially as shown.
